UNITED STATES PATENT OFFICE.

PAUL ORTMANN, OF ZITTAU, ASSIGNOR TO GUSTAV NATHAN, OF LEIPSIC GERMANY.

WINDOW-BLIND.

SPECIFICATION forming part of Letters Patent No. 544,371, dated August 13, 1895.

Application filed September 23, 1891. Serial No. 406,557. (No model.) Patented in Germany April 18, 1889, No. 50,792, and in England January 22, 1890, No. 1,189.

To all whom it may concern:

Be it known that I, PAUL ORTMANN, of Zittau, in the Kingdom of Saxony, Germany, have invented a new and useful Improvement in 5 Window-Blinds, (for which I have obtained a patent in England, No. 1,189, dated January 22, 1890, and in Germany, No. 50,792, dated April 18, 1889,) of which the following is a specification.

10 This invention relates to a window-blind composed of a series of flexible sections that may be either revolved similar to the ordinary slats or may be wound upon a drum.

The invention consists in the various features of improvement more fully pointed out 15 in the claims.

In the accompanying drawings, Figure 1 is a front elevation of my improved window-blind; Fig. 2, a top view thereof; Fig. 3, an 20 end view thereof; Fig. 4, a vertical cross-section on line I II, Fig. 1, with the key *k*, lowered; Fig. 5, a similar section with the key raised; Fig. 6, a top view of the blind with the 25 flexible slats inclined. Fig. 7 is a front elevation of part of a window-blind, showing a modification of my invention; Fig. 8, a vertical section on line M M, Fig. 7; Fig. 9, a top view of a modification; Fig. 10, a cross-section on line O O, Fig. 7; Fig. 11, a front elevation 30 of a further modification; Fig. 12, a vertical section on line P P, Fig. 11; Fig. 12^a, an end view of upper part of Fig. 11; Fig. 13, a section similar to Fig. 12 with bar *b'* disengaged from spring-rod *N'*; Fig. 14, a cross-section on 35 line T T, Fig. 11; Fig. 15, a top view of pin *y*.

With particular reference to Figs. 1 to 6, the letters *a a* represent a series of upright flexible strips secured at their upper and lower ends to short bars *b c* respectively, so 40 as to constitute a set of adjoining flexible slats. The lower bars *c* are pivotally connected to a rod *d*. The upper bars *b* are of semicircular shape in cross-section and are pivotally connected by pins *g* to a semicircular roller *e*, journaled in the window-frame. The parts *b e* together, when in line, form a 45 complete circular roller. A connecting-rod *f*, secured to all the bars *b*, serves to simultaneously incline the slats in the well-known man-

ner by the motion of a single slat. The upper bar of the central slat is marked *b'*, and to this bar is affixed a pin or arbor *h*, passing loosely through rod *e*. A key *k*, depending from the ceiling by a cord *n* and carrying a sheave *i*, may be raised or lowered by means 50 of said cord. When lowered, the key engages arbor *h*, and by pulling on either of a pair of cords *l m*, wound around a sheave *i*, the arbor is turned to revolve bar *b'*. The motion of bar *b'* is, by rod *f*, transmitted to the several slats, so that the same are opened, as in Fig. 6, or closed, as in Fig. 2. The roller *e* carries near one end a sheave *o'*, around which passes the cord *o*. After the key *k* has been raised to release arbor *h* the roller *e* may be 55 revolved by means of cord *o* to roll up the blind to any desired extent. Of course all the slats should be brought into line, as in Fig. 2, before the blind is rolled up.

In Figs. 7 to 10 there passes through one of 60 the lower bars *c'* a shaft *N*, free to be revolved by hand-wheel *R* in its bearings *t*. The shaft *N* is connected to a forked arm *u*, that engages slat *b'*, Fig. 9. By revolving shaft *N* the bars *c' b'* are likewise revolved. The latter, being by the rod *f* connected to the bars *c b* of all the other slats, cause the blind to 65 be opened to any desired extent.

In Figs. 11 to 15 the revolution of the slats is effected by a divided spring-shaft *N'*. The 70 lower end of this shaft sets in a socket of a crank *q*, pivoted to the window-frame. The upper spring end of the shaft engages a notch *w* of bar *b'* and is guided by a bearing *q'*. When the crank *q*, and with it the shaft *N'*, 75 is moved in an arc around the pivot of the crank, the shaft will impart an opening or closing motion to the slats by means of the rods *f*.

If the blind is to be wound upon the drum 80 *e*, the upper end of the spring-shaft is first drawn down to become disengaged from notch *w*, and to thus liberate bar *b'*.

In order to permit the opening and closing 85 of this blind by means of a cord, one of the bars *e* is provided with a downwardly-extending pin or pivot *y*, that carries a double sheave *i'*, surrounded by cords *x*. By revolving the

sheave the pin *y* will revolve its bar *c*, and this motion will, by rods *f*, be transmitted to the entire series of slats.

What I claim is—

- 5 1. The combination in a window blind of flexible slats pivoted at the top and bottom with means for rolling them up in the direction of their longer axes, and with means for simultaneously vibrating them on their pivots, substantially as specified.
- 10 2. The combination of a divided flexible blind, with bars *b*, secured thereto, a roller *e*, to which the bars are pivoted and rod *f*, connecting the blind sections, substantially as specified.
- 15 3. The combination of a divided flexible

blind with bars *b*, *c*, secured thereto, roller *e*, and rod *d*, to which the bars are respectively pivoted and rods *f*, connecting the blind sections, substantially as specified.

4. The combination of a divided flexible blind with roller *e*, and an arbor *h*, secured to one of the blind sections, a key *k*, for engaging the arbor and connecting rods *f*, substantially as specified.

In testimony whereof I have signed my name to this specification in the presence of two subscribing witnesses.

PAUL ORTMANN.
